CLAIM

I claim the ornamental design for a full longitudinally oriented oval aperture can, as shown and described.

DESCRIPTION

This application is related by subject matter to co-pending U.S. Application Ser. No. 12/797,171 filed Jun. 9, 2010, U.S. Application Ser. No. 29/363,492 filed Jun. 10, 2010, U.S. Application Ser. No. 29/363,498 filed Jun. 10, 2010, U.S. Application Ser. No. 29/363,500 filed Jun. 10, 2010, and U.S. Application Ser. No. 29/363,502 filed Jun. 10, 2010. This application is also related by subject matter to co-pending application Ser. No. 29/368,322, filed Aug. 23, 2010 entitled “Full Offset-Circular Aperture Can” and 29/368,324, filed Aug. 23, 2010 entitled “Full Transversely Oriented Oval Aperture Can”.

FIG. 1 is a top perspective view of an full longitudinally oriented oval aperture can according to our new design;

FIG. 2 is a side view thereof, with all sides being identical.

FIG. 3 a top plan view thereof; and,

FIG. 4 is bottom plan view thereof.

The portions of the drawings appearing in broken line are for environment only and do not form a part of the claimed design.
